R. A. McCANN

RAILWAY TRAFFIC CONTROLLING APPARATUS

Filed Nov. 17, 1924

UNITED STATES PATENT OFFICE.

ROLAND A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed November 17, 1924. Serial No. 750,317.

To all whom it may concern:

Be it known that I, RONALD A. McCANN, a citizen of the United States, residing at Swissvale, in the county of Allegheny and 5 State of Pennsylvania, have invented certain new and useful Improvements in Railway-Traffic-Controlling Apparatus, of which the following is a specification.

My invention relates to railway traffic controlling apparatus, and particularly to apparatus of the type comprising train carried governing means controlled by energy received from the trackway.

I will describe two forms of apparatus embodying my invention, and will then point out the novel features thereof in claims.

In the accompanying drawing, Fig. 1 is a diagrammatic view illustrating one form of 20 apparatus embodying my invention. Fig. 2 is a view showing a modification of the trackway portion of the apparatus illustrated in Fig. 1.

Similar reference characters refer to similar parts in both views.

Referring first to Fig. 1, the reference characters 1 and 1^a designate the track rails of a stretch of railway track, over which traffic normally moves in the direction indicated by the arrow. These track rails are divided, by means of insulated joints 2, into a plurality of successive track sections A—B, B—C, etc. Each track section is provided with a track relay designated by the 35 reference character R with an exponent corresponding to the location and connected across the rails adjacent the entrance end of the section. Each track section is also provided with a source of track circuit current here shown as a battery 7 connected, as will be explained hereinafter, across the rails adjacent the right hand end of the section.

Means are also provided for supplying 45 each track section with alternating current, which I shall call a "train controlling current", and which current flows through the rails of the section in series. For this purpose each section is provided with a track transformer designated by the reference character T with an appropriate exponent. The primary 4 of each track transformer T is constantly supplied with alternating cur-

rent from an alternator M over line wires 3 and 3^a.

An auxiliary conductor, here designated by the reference character J with a suitable distinguishing exponent, is located in the trackway adjacent the exit end of each section parallel to rail 1^a. The purpose of these auxiliary conductors will be explained hereinafter.

Referring particularly to section A—B, when relay R^B is energized a circuit is closed from secondary 5 of track transformer T^B, 65 through wires 12 and 13, front contact 14 of relay R^B, and wire 15 to rail 1^a of section A—B; and from rail 1 of section A—B, through wire 16, battery 7, wire 17, auxiliary conductor J^B, wire 18, impedance 6, 70 and wire 19 back to secondary 5 of transformer T^B. It will be plain that when this circuit is closed alternating train controlling current is supplied to the rails of section A—B and to auxiliary conductor J^B from transformer T^B, and at the same time track 75 circuit current is supplied to section A—B from battery 7. When relay R^B is de-energized battery 7 at point B is connected directly with the rails of section A—B over wires 23 and 24, back contact 14 of relay R^B, and wires 15 and 16. At the same time a circuit is closed from secondary 5 of transformer T^B, through wires 12 and 20, back 80 contact 21 of relay R^B, wires 22, 23 and 17, auxiliary conductor J^B, wire 18, impedance 6, and wire 19, back to secondary 5 of transformer T^B. When relay R^B is de-energized, therefore, track circuit current is supplied 85 to section A—B by battery 7 adjacent point B, and train controlling current is supplied to auxiliary conductor J^B from transformer T^B, but the supply of train controlling current to the rails of section A—B is discontinued. The circuits for the remaining sections are similar to those just traced for section A—B.

As shown in the drawing, the section to the right of point C is occupied by a train V. Relay R^C is therefore de-energized. As 100 a result section B—C is supplied with track circuit current from battery 7 adjacent point C, and auxiliary conductor J^C is supplied with train controlling current from transformer T^C, but train controlling current is 105 not supplied to the rails of section B—C.

Relay R^B is energized and so train controlling current is supplied to the rails of section A—B in series with auxiliary conductor J^B from transformer T^B , and section 5 A—B is also supplied with track circuit current from its battery 7. Relay R^A is therefore energized and the supply of track circuit current and train controlling current to the section to the left of point A is the same 10 as just described for section A—B.

The trackway circuits thus far described are suitable for co-operation with train carried governing means of the type illustrated on the train V' occupying the section to the 15 left of point A. Carried on train V' in advance of the front axle is a pick up device here shown as two magnetizable cores 8 and 8^a disposed in inductive relation with the track rails 1 and 1^a, respectively. Core 8 20 is provided with a winding 9, and core 8^a is provided with a similar winding 9^a, and these two windings are connected in series in such manner that the voltages induced therein by train controlling current flowing in opposite directions in the two track rails at 25 an instant are additive. Energy induced in windings 9 and 9^a is supplied to a relay K through an amplifier 10 and a rectifier 11. It follows, therefore, that relay K is energized when the train occupies a stretch of 30 track which is being supplied with train controlling current or when the winding 9^a is in inductive relation with an energized auxiliary conductor J. Relay K controls train 35 carried governing means, not shown in the drawing, in such manner that the brakes are applied when relay K is deenergized unless the engineman acknowledges this change by taking some deliberate action to forestall the brake application. One form of train 40 carried governing means which functions in this manner is illustrated and described in United States Letters Patent No. 1,492,719 granted to me on the 6th day of May, 1924. 45 As the train V' proceeds through the section to the left of point A and through section A—B, the train controlling current in the track rails energizes relay K, thus preventing an automatic brake application. Since relay K is already energized, no 50 change takes place as the train successively moves over auxiliary conductors J^A and J^B . As the train enters section B—C, relay K becomes de-energized due to the absence of 55 train controlling current, thus causing an automatic brake application unless the engineman acknowledges. If the engineman does acknowledge, the train can proceed until core 8 of the train passes over auxiliary conductor J^C , whereupon relay K becomes 60 energized. When the train-carried pick up device has moved past auxiliary conductor J^C , relay K is again de-energized, and the engineman must again acknowledge to prevent 65 an automatic application of the brakes.

I will assume that the stretch of track shown in the drawing is unoccupied. All 70 relays R are then energized, and train controlling current is supplied to the rails of each section through the associated auxiliary conductor J and track battery 7. If conductor J^C becomes broken, or its circuit becomes interrupted, the supply of both train controlling current and track circuit current to the rails of section B—C is interrupted. Relay R^B therefore is de-energized and section A—B is supplied with track circuit current but not with train controlling current and conductor J^B is supplied with train controlling current directly 80 from transformer T^B . If now a train V' enters section A—B the engineman will be forced to acknowledge at point A, and again at conductor J^B . It is therefore plain that with circuits embodying my invention, the 85 integrity of the circuits for the auxiliary conductors is checked by using substantially these same circuits for supplying train controlling current and track circuit current to the rails of the corresponding section under safe traffic conditions. 90

Under some conditions of operation it may be desirable to divide the section into two sub-sections. Under such conditions the arrangement of apparatus illustrated in 95 Fig. 2 may be used. In this view only one section, A—B, is shown and the section is divided, by means of insulated joints 2, into a rear sub-section A—G and a forward sub-section G—B. Relay R^A is connected across 100 the rails adjacent the entrance end of section A—B and relay R^B is connected across the rails adjacent the entrance end of the section to the right of point B, as in Fig. 1. In addition, a track relay R^2 is connected across 105 the rails adjacent the exit end of sub-section G—B and a similar relay R' is connected across the rails adjacent the exit end of the section to the left of point A. Each section is provided with an auxiliary conductor J 110 as in Fig. 1. A track battery 7 is connected across the rails of sub-section G—B adjacent point G and track circuit current is therefore constantly supplied to the rails of sub-section G—B. Sub-section A—G is provided with a track transformer T^G having a secondary winding 5 constantly connected across the rails adjacent the exit end of sub-section A—G in series with a track battery 115 7. When relay R^B is energized, current is supplied from line wire 3, through wire 28, front contact 21 of relay R^B , wire 29, primary 4 of transformer T^G , and wire 30 back to line wire 3^a. When this circuit is closed 120 train controlling current is supplied to the rails of sub-section A—G. When relay R^2 is de-energized, track transformer T^B is supplied with alternating current from line wire 3, through wire 25, back contact 26 125 of relay R^2 , wire 26^a, primary 4 of trans- 130

former T^B , and wire 27 back to line wire 3^a . When transformer T^B is thus supplied with current and relay R^B is energized current flows from the secondary 5 of transformer T^B , through wire 12, front contact 14 of relay R^B , wire 15, to rail 1 a of sub-section G—B, and from rail 1 of sub-section G—B, through wire 17, auxiliary conductor J^B , wire 18, impedance 6, and wire 19, back to secondary 5 of transformer T^B . It follows that when relay R^2 is de-energized as by the entrance of a train into sub-section G—B, and when relay R^B is energized, train controlling current is supplied to the rails 15 of sub-section G—B in series with auxiliary conductor J^B . If, however, relay R^2 and relay R^B are both de-energized train controlling current is supplied only to auxiliary conductor J^B from secondary 5 of transformer T^B , through wire 12, back contact 14 of relay R^B , wires 24 and 17, auxiliary conductor J^B , wire 18, impedance 6, and wire 19, back to transformer T^B ; under these conditions the supply of train controlling current to sub-section G—B is interrupted. As shown in the drawing the track is unoccupied, so that relays R' , R^A , R^2 and R^B are all energized. If, now, a train provided with the apparatus shown on train V' in Fig. 1, should enter section A—B, relay K would be energized due to the train controlling current supplied to sub-section A—G, by transformer T^c . When the train enters sub-section G—B the deenergization of relay R^2 will complete the primary circuit for transformer T^B , and since relay R^B is energized train controlling current will be supplied to the rails of sub-section G—B and auxiliary conductor J^B , and relay K on the train will be maintained in its energized condition.

I will now assume that the section to the right of point B is occupied by a train. Relay R^B is therefore de-energized and the supply of train controlling current to both sub-sections A—G and G—B is interrupted. I will also assume that a train enters section A—B. Relay K on the train will become de-energized and will remain in its de-energized condition through sub-section A—G, and in sub-section G—B as far as auxiliary conductor J^B . When the train passes over auxiliary conductor J^B , relay K will be energized and the relay will be de-energized again when the train leaves auxiliary conductor J^B , thus requiring the engineman to acknowledge in order to prevent an automatic application of the brakes.

I will now assume that relay R^B is energized, but that the circuit including auxiliary conductor J^B is interrupted, as by a broken wire. Obviously the supply of train controlling current to sub-section G—B is interrupted but the supply of train controlling current to sub-section A—G is not

affected. Should a train enter section A—B under these conditions, relay K would be de-energized as the train passed point G and the engineman would be required to acknowledge to prevent an automatic brake application.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. Railway traffic controlling apparatus comprising a stretch of railway track, an auxiliary conductor located adjacent said stretch, a source of alternating current located in the trackway, and means for at times causing current from said source to flow through said conductor and the rails of said stretch in series, and for at other times causing current from said source to flow through said conductor but not through the rails of the stretch.

2. Railway traffic controlling apparatus comprising a stretch of railway track, a source of direct current, a track relay responsive to such current, a source of alternating current, an auxiliary conductor adjacent said stretch, and means controlled by said track relay for at times connecting said alternating current source in series with said direct current source and said conductor and the rails of said stretch, and for at other times connecting said direct current source directly with the rails and simultaneously connecting the alternating current source with the auxiliary conductor but not with the rails of the stretch.

3. In combination, a forward and a rear section of railway track, an auxiliary conductor adjacent said rear section, a source of alternating train controlling current located in the trackway, and means controlled by traffic conditions in said forward section for at times causing current from said source to flow in series through said conductor and the rails of said rear section and for at other times causing current from said source to flow through said conductor but not through the rails of said rear section.

4. In combination, a stretch of railway track, train carried governing means responsive to alternating current in the trackway, an auxiliary conductor located in the trackway, a source of alternating current located in the trackway, and means responsive to traffic conditions in advance for at times connecting said source with said conductor through the rails of the stretch in series and for at other times causing current from the source to flow through said conductor but not through the rails of the stretch.

5. In combination, a stretch of railway track, train carried governing means responsive to alternating current in the trackway, an auxiliary conductor located in the trackway, a source of alternating current, a source of direct current, a track relay responsive to such current, means controlled by said track relay for at times connecting said alternating current source with said conductor 10 with said direct current source and the rails of said stretch in series and for at other times connecting said alternating current source directly with said auxiliary conductor and for simultaneously connecting said direct current source directly with the rails of the stretch.

6. In combination, a stretch of railway track comprising a forward and a rear section of railway track, a track relay responsive to traffic conditions in said forward section, a source of alternating current and a source of direct current for said rear section; a circuit for said rear section including said alternating current source, said direct current source, the rails of said rear section in series and a front contact of said track relay; a second circuit including the rails of said rear section, said direct current source and a first back contact of said track relay; a third circuit including said alternating current source, said auxiliary conductor and a second back contact of said track relay; trackway governing means responsive to direct current in the rails of said rear section, and train carried governing means responsive to alternating current in the trackway.

7. In combination, a forward and a rear section of railway track, a source of direct current connected with the rails of said rear section, a track relay connected across the rails adjacent the exit end of said rear section, an auxiliary conductor adjacent the exit end of such rear section, a transformer, means controlled by said relay for at times supplying alternating current to the primary of said transformer, means responsive to traffic conditions in said forward section for at times supplying alternating current from

the secondary of said transformer to said conductor and the rails of said rear section in series and for at other times supplying such current from said secondary to said conductor but not to said rails, and train carried governing means responsive to alternating current in the trackway.

8. Railway traffic controlling apparatus comprising a stretch of railway track, an auxiliary conductor located adjacent said stretch, a source of alternating current located in the trackway, and means controlled by traffic conditions in advance of the stretch for at times supplying current to said conductor and to the rails of the stretch in series from said source and for at other times causing current from said source to flow through said conductor but not through said rails.

9. Railway traffic controlling apparatus comprising a stretch of railway track divided into a plurality of successive sections, an auxiliary conductor for each section, a source of track circuit current for each section, a track relay for each section responsive to track circuit current in the associated section, a source of train controlling current for each section, and means for each section including the track relay for the section next in advance for at times supplying said auxiliary conductor and the rails of the associated section in series with train controlling current and for at other times supplying train controlling current to the auxiliary conductor but not to the rails of said stretch.

10. A section of railway track, a track relay connected with the rails in advance of said section, an auxiliary conductor for said section, a source of direct track circuit current, a source of alternating train controlling current, and a circuit including said alternating current source, said direct current source, said auxiliary conductor, the rails of the section, and a front contact of said track relay.

In testimony whereof I affix my signature.

RONALD A. McCANN.
